(57) **CLAIM**

The ornamental design for an orthodontic rubber band applicator, as shown and described.

DESCRIPTION

FIG. 1 is a right side elevation view of an orthodontic rubber band applicator showing my new design, the left side elevation view being the mirror image thereof;

FIG. 2 is a top plan view thereof;

FIG. 3 is a bottom plan view thereof;

FIG. 4 is a rear elevation view thereof; and,

FIG. 5 is a front elevation view thereof.
